UNITED STATES PATENT OFFICE.

FREDERICK H. HAWKINS, OF NEW YORK, N. Y.

MACHINE FOR EMBOSSED DESIGNS ON WOOD.

SPECIFICATION forming part of Letters Patent No. 448,485, dated March 17, 1891.

Application filed April 22, 1890. Serial No. 349,053. (No model.)

To all whom it may concern:

Be it known that I, FREDERICK H. HAWKINS, a subject of the Queen of Great Britain, residing at 550 East One hundred and forty-third street, in the city of New York, and county and State of New York, have invented certain new and useful Improvements in Machines for Embossing Designs on Wood or other Material, of which the following is a specification.

My invention has relation to improvements in machines for embossing designs on wood and other material; and it has for its object to provide a machine of the character mentioned thoroughly adapted to emboss all forms and kinds of wood and the like with various appropriate and ornamental designs.

The improvements will be fully understood from the following description and claims, when taken in connection with the accompanying drawings, in which—

Figure 1 is a side elevation of my improved machine, the parts being illustrated in an operative position with a piece of stock between the embossing-rolls. Fig. 2 is a front elevation of the same. Fig. 3 is a detail plan view of the bed of the machine, the movable pressure elements being removed and the upright standard illustrated in horizontal sections. Fig. 4 is a detail side view illustrating the relative positions of the embossing-rolls and the piece of stock when adjusted for heavy work.

Referring by letter to the said drawings, a indicates the bed or base frame of the machine, which may be cast or otherwise formed in any approved manner. Preferably formed integral with and rising from the bed *a* is an upright standard *C*, which is provided at its upper end with an integral forwardly-extending angular branch *i*, for a purpose presently to be described. This standard *C*, as illustrated at *S* in Fig. 3, is provided with an opening or recess at its base, whereby a passage is afforded for that class of work which is fed longitudinally through the machine. Mounted on suitable bearings on either side of the rear upper end of the bed or base frame *a* is a forwardly-disposed pivoted section *g*, comprising two arms or branches, and these arms or branches have journaled between them at their forward ends in suitable

bearings *t* an embossing die or roll *h*, which rests over the space between the two lower dies *h'* *h''*, presently to be described, and one of the arms of the section *g* has suitably mounted upon it a train of gears which transmit motion from the pulley-shaft to a pinion upon the end of the shaft carrying said embossing-roll *h*. By this construction and mounting of the section *g* it will be seen that its forward and free end is allowed a vertical play of several inches, whereby the dies may be adjusted to emboss stock of various sizes.

Suitably journaled in the forwardly-extending branch *i* of the standard *C* and adjacent to the forward end thereof is a gear-wheel *K*, upon the ends of the shaft of which are fixed cams *m*, which bear upon the upper side of and regulate the pressure of the roll *h*, journaled in the free end of section *g*.

The gear *K* is actuated by a worm-gear *Y*, mounted on the top of the branch *i* and meshing with said gear *K*, and mounted on the forwardly-extending portion of the shaft of said worm-gear *Y* is a hand-wheel *W*, whereby the same may be readily operated. Fixed on the shaft carrying the gear *K* is a band-wheel *K'*, to the periphery of which is attached the upper end of a strap *V*, which may be formed of any approved material, and is attached at its lower end to the free end of the pivoted section *g*. On each side of the pivoted frame *g*, adjacent to the forward end thereof, are pivotally-connected hangers *n*, the lower ends of which are pivotally connected to the forward ends of bars *n'*, which are suitably mounted in a pivoted manner on each side of the bed *a* adjacent to the rear upper end thereof. Pivotally connected to the bars *n'* at a suitable intermediate point are depending tension-bars *n''*, which in turn have their lower ends pivotally connected at an intermediate point in the length of weight bars or levers *n'''*, which are pivotally connected to the sides of the bed *a* adjacent to the forward lower end thereof. These bars *n'''* are provided with apertures at intermediate points, as illustrated, whereby the lower end of the tension-bar *n''* may be adjustably connected thereto, and the said bars or levers *n'''* carry at or adjacent to their free ends weights *n⁴*, which are provided with binding-screws or the like, whereby they may be ad-

justably fixed on the said levers n^3 . By this construction it will be seen that I have provided a positive means for exerting a pressure upon and holding the free end of section 5 g down and carrying the engraving-die to a certain regulated point; and it will also be seen that through the medium of the band-wheel K' and the strap V , I am enabled to readily raise the pivoted or swinging section 10 from the stock when desired. It will also be observed in the preceding description that in the tension-levers and weighted arms I have provided a medium whereby the embossing-die h is allowed a limited yielding movement.

15 The lower dies h' and h^2 are carried by movable bearings or carriages o and o' , and they are adjusted to suit various sizes of stocks by means of pinions o^2 , which are mounted on a shaft-bearing in the carriages 20 carrying the shafts of the embossing-rolls, and these pinions o^2 mesh with the teeth or cogs of segmental bases or tracks p' formed on the upper forward end of the bed or base a . By this construction it will be seen that 25 the lower rolls h' and h^2 may be given a curvilinear receding and approaching motion on the segmental bases, and by the employment of such rollers I am enabled to operate upon round articles—such as stair-banisters and 30 similar articles—the stock being allowed to turn while being operated upon by the engraving-die.

As better illustrated in Fig. 1 of the drawings, the gearing actuating the lower embossing-dies h' and h^2 is connected together by means of a rod p , whereby when the adjustable bearings of said rolls are moved the train of gearing is not broken.

When the lower dies have been properly 40 adjusted with respect to the stock to be operated upon, I secure the adjustable bearings or carriages thereof to the segments by means of bolts a^2 or the like, which take through the bearings into apertures formed at intermediate points in the periphery of said segments; but I do not desire to limit myself to this construction for fixing the bearings on the segments, as it is obvious that any suitable devices might be employed for the purpose.

45 In Fig. 4 of the drawings I have illustrated a diagram to show the relative positions of the embossing dies or rolls when used for very heavy work, and it will be observed that for this class of work I employ in addition to the upper die h and the two lower dies h' and h^2 a third lower die h^3 , which bears in movable bearings adjustable upon the segments p' , and when it is desirable to accomplish the embossing with the top die alone a roller of a 50 diameter to carry the stock clear of the dies h' and h^2 is employed, and these dies, as are those illustrated in position upon the machine, are driven by the pulleys X , the gear X' , and the train of gears illustrated.

55 In operation the lower embossing-dies h' and h^2 are adjusted to the size of the stock, and are secured in such position, as described.

The pivoted section g is then raised a sufficient height, through the medium of the hand-wheel W and the strap V , as described, to allow of the introduction of the stock between the dies, and from the construction described it will be seen that when the machine is set in motion and the dies are rotated the stock (indicated by W') will be rotated between the 75 dies until the desired result is attained.

From the foregoing description it will also be understood that when desired stock may be fed lengthwise through the machine, the opening S in the upright standard C being 80 provided for that purpose.

What I claim as my invention, and desire to secure by Letters Patent, is—

1. In a machine for ornamenting wood and other suitable material, the combination, with 85 the main frame, of a die-carrying frame pivoted thereon, a strap for suspending the outer end of the die-carrying frame from the main frame, a cam for depressing the die-carrying frame, and gearing for elevating said frame, 90 substantially as specified.

2. The combination, with the main frame, of the standards rising therefrom and carrying horizontal arms, a worm-gear journaled between the arms, cams fixed to the outer 95 ends of the shaft carrying the worm-gear, a power-gear also journaled on the horizontal arms and meshing with the worm-gear, a die-carrying frame journaled in the main frame, and a strap connecting the outer end of the 100 die-carrying frame with the worm-shaft, substantially as specified.

3. In a machine substantially as described, the combination, with the main frame having the segmental bearings, of the journal boxes 105 or blocks mounted thereon, the ornamenting-rolls journaled in said blocks, and the shafts carrying pinions also mounted in said blocks, substantially as specified.

4. The combination, with the main frame, 110 of the upper die or roll carrying frame pivoted at one end therein, the lower rolls bearing on the main frame, the arm pivoted at one end to the main frame and having its opposite end connected with the outer end of the die-carrying frame, the weighted lever pivoted at one end to the main frame, and the tension-bar connecting the weighted lever with the upper arm, substantially as specified.

5. The combination, with the main frame, 115 of the pivoted die-carrying frame, means for elevating the outer end of the die-carrying frame, cams for depressing said frame, and the weighted lever and arms connecting the same to the pivoted die-carrying frame, substantially as specified.

6. The main frame having a segmental bearing-face, in combination with the lower dies, blocks seated on the segmental face and supporting the dies, gearing for rotating said dies, 130 and the pinions and shafts for moving the bearings of the lower dies, substantially as specified.

7. In a machine for embossing designs on

turned or irregular-shaped articles of wood or other materials, the combination of the frame *a*, the standard *c*, the adjustable frame or arm *g*, the fixed arm *i*, the device for raising the arm *g*, consisting of the hand-wheel *W*, the worm *Y*, wheel *K*, cam *m*, and strap *V*, the dies *h*, *h'*, and *h²*, with their shafts and driving-gear, the pressure device consisting of the hanger *n*, the bar *n'*, the tension-bar *n²*, the lever *n³*, and weight *n⁴*, and the driving-gear, all substantially as shown, and for the purpose specified.

8. In a machine for ornamenting wood and

the like, the pivoted arm and the upper rotatable die carried thereby, in combination with the tension device connected with said arm, a set of lower rotatable dies movably supported upon a segmental base, and means for operating said dies, whereby both the upper and lower dies may be rotated and moved to and from one another, substantially as specified.
